UNITED STATES PATENT OFFICE.

FRANK N. HOLZINGER, OF PEORIA, ILLINOIS.

KEY-FASTENER.

1,287,316.

Specification of Letters Patent. Patented Dec. 10, 1918.

Application filed November 14, 1916. Serial No. 131,308.

To all whom it may concern:

Be it known that I, FRANK N. HOLZINGER, a citizen of the United States, residing at Peoria, in the county of Peoria and State of Illinois, have invented certain new and useful Improvements in Key-Fasteners, of which the following is the specification.

My invention relates to a key fastener or means to secure a key against turning through tampering therewith by a tool inserted into the key hole from the outside.

I aim to provide a novel form of device of this nature capable of manufacture at low cost, and improved particularly with respect to the provision of a novel means to fasten the device in engagement with the key; to provide a mounting block with one or more elongated grooves receiving ends of the fastener and leading into sockets into which said ends clip, and also to provide a means to maintain the said ends in said socket and as well brace the fastener against distortion should it be attempted to operate the key.

With the above and additional objects, such as will hereinafter appear, in view, the invention has been embodied in one preferred form as illustrated in accompanying drawings wherein:—

Figure 1 is a perspective view illustrating my improvements applied to a door key, which is shown in connection with fragments of the door and the lock;

Fig. 2 is a cross sectional view taken across my improved device along the line 2—2 of Fig. 1, and

Fig. 3 is a vertical sectional view taken through the mounting block.

Referring specifically to the drawings, I have shown a conventional key at 4 in connection with a door lock 5 of a door 6. Such parts are to be taken merely as representative, since the improvements are capable of use in connection with keys generally, although the device is particularly capable of use in connection with door keys. Such keys are oftentimes tampered with, for instance on the part of burglars, when they remain in the key hole, being inserted from the inside, as is customary. A tamperer operating from the outside, oftentimes tries to dislodge the key. My improvements mount it so that it cannot be turned by tampering from the outside and as a result cannot be dislodged from the key hole.

In carrying out my improvements, I pro-

vide a preferably one piece fastening member of spring or resilient wire although other material may suffice. This member has elongated side arms 7 joined by a bridge at the top and which is shaped to provide a fastening lobe or lug at 8 and also to provide shoulders at 9. The arms 7 incline, being closer together at their base than at the bridge, and both inclining to the same extent from the vertical median line. As the arms are thus upwardly inclined, a clasp, brace and adjuster 10 may be moved longitudinally of the arms to vary the distance between the arms at their base.

Secured to the door as by means of screws 11, is a mounting block 12. At the side of this mounting block, elongated grooves 13 are provided and each groove leads to an inwardly extending socket 14. Into the sockets 14 extend pivot lugs 15 formed substantially at right angles to and integral with the arms 7.

Member 10 may be of any suitable construction but preferably comprises a single strip of metal having flanges 16 bent around the arms 7 as shown.

Normally the fastener 7 depends vertically from the mounting block with the lugs 15 at the lower end of the recesses or grooves 13. To enable these lugs 15 to disengage the sockets 14 and then move in the grooves 13, the adjuster 10 must first be lowered. In order to fasten the key, after it has been inserted, it is made to occupy the position shown in Fig. 1. The fastener is then swung upwardly and pushed upwardly so that the lug 8 extends through the openings of the bow of the key with the shoulders 9 engaging the key. The arms 7 are tensioned so that they will clip into the grooves 13 to prevent detachment of the arms 7 from the block 12 but are not tensioned sufficiently to permit the lugs 15 to clip into the sockets 14. Therefore after the fastener is brought into fastening engagement with the key, the adjuster 10 which is adjacent the block 12 is moved toward the key and since the arms 7 are inclined, it will move the arms inwardly and force the lugs 15 into the sockets 14 thus fastening the fastener in place. The fastener will remain in adjusted position due to the friction between the flanges 16 and the arms 7.

In addition to the function set forth, adjuster 10 serves to brace the arms 7 adjacent the key and thus if the key should be turned,

there would not be sufficient movement to distort the fastener, to permit turning of the key.

Since merely the preferred embodiment has been illustrated and described, it is to be understood that changes in the details of construction may be resorted to within the spirit and scope of the invention as defined by appended claims.

10 I claim:

1. A key fastening device including a fastener means, a mounting means for said fastener means and having sockets therein, said fastener means having resilient arms, 15 means for contracting the arms for causing the free ends thereof to enter the sockets, said arms being initially movable relatively to the said mounting means to key-engaging position and being also movable in a plane 20 at an angle to the path of the initial movement thereof, and means to engage the resilient arms to support the fastener in key-engaging position.

2. A key fastening device including a fastener member, a mounting member therefor, said member having converging arms, 25 one of said members having a groove in which said arms are movable, means through which said groove leads to receive said arms, 30 and to support the fastener member in fastening position, said fastener member being movable into engagement with said means.

3. A key fastener device including a fastener, a mounting member therefor, said 35 mounting member having a groove and a socket to which said groove leads, said fastener having arms, one of said arms being inclined, means on one of said arms movable in said groove and tensioned to normally 40 remain therein, and means movable longitudinally of the arms cooperating with the inclined arm to move the same so that said means will extend into said socket.

4. A key fastening device including a key 45 fastener, a mounting therefor, said mounting having a supporting means for the fastener, said fastener and supporting means being normally disengaged to permit move-

ment of the fastener relatively to the key, and means associated with the fastener to 50 maintain the fastener in operative relation to the supporting means.

5. A key fastening device including a fastener, said fastener having arms, a mounting member for the fastener, said mounting member having a groove, a lug on one of said arms, said arms being tensioned so that said lug will normally remain in said groove, said mounting member having a socket, and means coöperating with the arms to move them relatively so that said lug will enter said socket.

6. A key fastening device including a fastener having elongated arms joined by a bridge, said bridge having a portion to 65 extend through the bow of a key and having shoulders, to be directly engaged by the key, and said arms extending downwardly and inwardly from the key and at their base terminating in lugs, a mounting member, 70 said mounting member being provided with grooves into which said lugs normally extend, said mounting member also being provided with sockets to which said grooves lead, means movable longitudinally of the 75 arms to move the arms relatively and said lugs into said sockets, and said means serving to brace the fastener adjacent the bridge against distortion through attempted turning of the key.

7. A key fastener device including a fastener member having a pair of converging arms, a mounting member therefor, and a bridge interposed between said arms and integral therewith, a lug formed on said 85 bridge to engage the key when said arms are in elevated position, and means movable longitudinally with the converging arms co-operating therewith to move them so that said arms will extend into said socket. 90

In testimony whereof I affix my signature in presence of two witnesses.

FRANK N. HOLZINGER.
